ANTENNA SYSTEM

Oakley M. Woodward, Jr., Princeton, N. J., assignor to Radio Corporation of America, a corporation of Delaware

Application September 29, 1945, Serial No. 619,401

8 Claims. (Cl. 250—33.65)

1

This invention relates to antennas, and more particularly to improvements in multi-element arrays wherein a plurality of radiators are energized from a single source or connected to a single utilization circuit.

In usual high frequency arrays, the radiators are resonant dipoles, often having impedances of the order of 50 to 70 ohms. These impedances are of the same order as the characteristic impedances of standard commercially obtainable coaxial transmission lines, so that ordinarily the dipoles can be coupled directly to the lines without requiring impedance transformers. However, in some cases, such as when the radiators are mounted close to a conductive reflector, the individual antenna impedance is so much lower that some impedance matching device is required. Most impedance matching devices comprise resonant elements whose characteristics are superimposed upon those of the radiators, seriously limiting the width of the band of frequencies through which the system will operate efficiently.

Accordingly, it is the principal object of this invention to provide an improved method of and means for connecting a plurality of dipole antennas in series with each other to a common feed line.

Another object is to provide an improved type of antenna structure which is simple and rugged in construction and easily designed to provide efficient operation throughout a wide frequency band.

The foregoing and other objects will become apparent to those skilled in the art upon consideration of the following description, with reference to the accompanying drawing, wherein:

Figures 1 and 2 are views in plan and elevation respectively of one antenna structure embodying the instant invention.

Figure 3 is a schematic diagram of an equivalent circuit of the system of Figure 1, and

Figure 4 is a view partly in section, of another embodiment of the present invention.

Referring to Figures 1 and 2, a tray or pan-like structure 1 is provided with end walls 3 and 5 and a central partition 7. The over-all length is substantially one wavelength at the mean frequency of operation of the system. A coaxial transmission line 9 extends through the end wall 3 and the partition 7, terminating on the end wall 5. The outer conductor of the line 9 is connected to the walls 3, 5, and 7 where it passes through them. The inner conductor of the line 9 may stop short of the wall 5 as shown, or may be con-

2

nected thereto, since it is connected to the outer conductor at a point near the wall 5 by a shorting plug 11.

The outer conductor of the line 9 is provided with diagonal slots 13 and 15 at points midway between the wall 3 and the partition 7 and midway between the wall 5 and the partition 7 respectively. These slots break the outer conductor into three sections 17, 19 and 21. The section 21 is one-quarter wavelength long. The section 19 is one-half wavelength long, grounded at its center by its connection to the partition 7. The portion of the section 17 within the pan 1 is one-quarter wavelength long.

The inner conductor of the line 9 is not broken, but extends continuously through to the shorting plug 11. The portion of the inner conductor within the section 19 may be made of somewhat greater diameter than the remainder, for a purpose explained hereinafter, or the inner conductor may be of the same diameter throughout.

A pair of radiator elements 23 and 25 are connected to members 17 and 19 respectively on opposite sides of the gap 13. Similar radiator elements 27 and 29 are connected to members 21 and 19 respectively at the gap 15. In the present illustration, the radiators are spaced about 0.1 wavelength from the surface of the pan 1. However, this spacing may be made greater or less, in accordance with various design considerations.

The operation of the described system is as follows:

The outer conductor section 21 cooperates with the surface of the pan 1 to act as a quarter wavelength line section, short-circuited at one end by the wall 5 and therefore presenting a high impedance at the other end. The end of the section 21 adjacent the gap 15 is thus effectively isolated from ground at the frequency of operation.

Similarly, the left-hand portion of the section 19, grounded at the partition 7, provides a high impedance adjacent the gap 15. Thus each of the dipole elements 27 and 29 is separated from ground by the high impedance of a shorted quarter wave line. The elements 23 and 25 are similarly isolated from ground by the right-hand portion of the section 19 and the left-hand end of the section 17.

When the system is to be used for transmission, energy is applied to the open end 31 of the line 9. The directions of current flow at a particular instant of the radio frequency cycle are indicated

in Figure 1 by the arrows adjacent the various elements. At every point on the line 9, the current in the outer conductor is necessarily equal and opposite to that in the inner conductor. Thus a current flowing from right to left on the inner conductor within the section 17 causes an equal current to flow inward on the radiator 23 and thence from left to right on the outer conductor section 17. Similarly, the same current flowing from right to left into the inner conductor within the section 19 requires an equal current to flow from left to right on the outer conductor section 19, and thence outward on the radiator 25. The radiators 23 and 25 are thus excited as elements of a dipole with equal currents flowing in on one and out on the other.

When current flows into the line section 19 at the gap 13, an equal current flows into it at the gap 15, corresponding to a phase difference of 180° between the currents at the two ends of the half wavelength line section between the gaps 13 and 15. Thus the current flows outward on the radiator 29, and inward on the radiator 27, through the conductor 21, the plug 11, and from left to right on the inner conductor within the section 21.

The section 21, the conductor inside it, and the plug 11, cooperate to function as a short-circuited "stub" line in series with the radiators 27 and 29. This stub is not required unless the system is to be tuned to a frequency other than that at which the radiators are naturally resonant. If it is used, the plug 11 is placed at such a position that the reactance of the stub is equal to and of opposite sign to the sum of the reactances of the two dipoles.

By virtue of the above described arrangement, the current applied to the line 9 flows serially through the two dipoles, so that the impedance presented to the feed line is twice that of each dipole. The inner conductor within the half wave section 19 may be made of larger diameter to lower the characteristic impedance of this portion to match the dipoles 27 and 29, although this is not necessary to the satisfactory operation of the system.

Referring to Figure 3, the impedances of the dipoles 23, 25 and 27, 29 are represented by the blocks 33 and 35 respectively. The parallel-resonant impedances of the quarter wave lines formed by the pan 1 and the sections of the outer conductor of the line 9 are represented by the circuits 31, 39, 41 and 43. The impedance of the stub formed by the plug 11 is represented by the block 45. Since the impedances 33 and 35 are equal to each other, and the impedances 37, 39, 41 and 43 are all alike, the voltages applied to all of the radiators are equal.

Although the invention has been described with reference to a system comprising two series-connected dipoles, it will be apparent that it may be extended to any number of series radiators. Referring to Figure 4, a coaxial line 9 has its outer conductor cut at a plurality of points 13, 15 at half wave intervals. Dipoles are connected across the gaps, as in the system of Figure 1. The half wavelength sections are surrounded by conductive sleeves 41, connected at their midpoints to the midpoints of the corresponding half wavelength outer conductor sections. The operation of the system of Figure 4 is substantially identical with that of Figure 1. It will be apparent without further illustration that the connections of every other dipole could be reversed, if desired, by cutting all the slots in the same direction,

without altering the series-connected operation. Moreover, the spacing between adjacent dipoles need not be one-half wavelength, but may be made different for certain applications by filling the short-circuited quarter wave sections, or the feed line, or both, with dielectric material.

I claim as my invention:

1. A radio antenna system including a coaxial feed line comprising a continuous inner conductor and an outer conductor surrounding said inner conductor, said outer conductor comprising a series of collinear sleeves, with the adjacent ends of each pair of sleeves spaced apart longitudinally; a plurality of radiator elements, one connected at each end of each of said sleeves, and conductive means at least partially surrounding said sleeves and in contact therewith only at the midpoints of said sleeves, whereby each pair of adjacent radiator elements functions as a doublet, and all of said doublets are electrically in series with each other across said feed line.

2. A radio antenna including a coaxial line comprising an inner conductor and an outer conductor, said outer conductor having a series of gaps at intervals along its length, a plurality of dipoles, one at each of said gaps, and each including two radiator elements connected to said outer conductor respectively at opposite sides of the respective gap, and a further conductor extending generally parallel and in spaced relationship to said outer conductor, and connected thereto at points midway between said gaps.

3. A radio antenna including a coaxial line comprising an inner conductor and an outer conductor, said outer conductor having a series of gaps at half wavelength intervals along its length, a plurality of dipoles, one at each of said gaps, and each including two radiator elements connected to said outer conductor respectively at opposite sides of the respective gap, a further conductor extending generally parallel and in spaced relationship to said outer conductor, and connected thereto at points midway between said gaps, and a reactance element connected to one end of said inner conductor and the corresponding end of said outer conductor.

4. The invention as set forth in claim 3, wherein said further conductor comprises a reflector for said antenna.

5. A radio antenna system including a transmission line comprising one continuous conductor and a second conductor parallel thereto and provided with a series of gaps spaced longitudinally thereof; a plurality of dipoles each disposed adjacent one of said gaps and each comprising two radiator elements connected to said second conductor respectively on opposite sides of the respective gap, and a third conductor parallel to said line and connected to said second conductor at points midway between said gaps.

6. A radio antenna system including a transmission line comprising one continuous conductor and a second conductor parallel thereto and provided with a series of gaps at half wavelength intervals; a plurality of dipoles each disposed adjacent one of said gaps and each comprising two radiator elements connected to said second conductor respectively on opposite sides of the respective gap, a third conductor parallel to said line and connected to said second conductor at points midway between said gaps, and a reactance element connected between one end of said first conductor and the corresponding end of said second conductor.

7. An antenna system including a substantially

rectangular pan-shaped body of conductive material substantially one wavelength long, provided with a transverse partition of conductive material midway of its length, a coaxial line extending through one end of said body, midway and lengthwise thereof and through said partition to the other end of said body, with its outer conductor connected to said ends and to said partition, said outer conductor being provided with two slots, each midway between said partition and one of said ends and two doublet antennas, each connected across one of said slots.

8. The invention as set forth in claim 5, including a reactance element connected between

one end of said inner conductor and said outer conductor.
